COMPRESSOR

William Felzer and Sam Weinberg,
San Francisco, Calif.

Application February 5, 1944, Serial No. 521,210

5 Claims. (Cl. 230—108)

This invention relates to a rotary compressor.

Several objects of this invention are the provision of a simple, balanced, easily manufactured and efficient compressor.

Another object of the invention is the provision of a compressor that is free from objectionable overheating.

A still further object of the invention is the provision of a compressor that overcomes lubrication problems such as have heretofore been encountered in most rotary compressors.

Other objects and advantages will appear in the specification and in the drawings annexed hereto.

In the drawings:

Fig. 1 is an elevational view of one form of our improved compressor in a closed housing with the walls of the latter being in section.

Fig. 2 is a diagrammatic view illustrating the action of the compressor of Fig. 1 through one cycle of compression.

Fig. 3 is an enlarged part-sectional, part-elevational view of the compressor of Fig. 1 in which the parts in section are generally taken along line 3—3 of Fig. 4.

Fig. 4 is a sectional view taken along line 4—4 of Fig. 3.

Fig. 5 is a part-sectional, part-elevational view of a slightly different form of compressor than is shown in the preceding views.

Fig. 6 is a sectional view taken along line 6—6 of Fig. 5.

Fig. 7 is a part-sectional, part-elevational view of a slightly different form of compressor than is shown in the preceding figures.

Fig. 8 is a sectional view taken along line 8—8 of Fig. 7.

Before describing the compressors of this invention in detail, it is to be understood that they are equally adapted to function as vacuum pumps, which is the case with most compressors.

Description of Figs. 1 to 4

In detail, the compressor illustrated in these figures comprises a face plate 1 (Fig. 4) having a flat side from which an annular ring 2 projects. This ring 2 is rigidly secured to the face plate and is flat, like an annular band. The ring 2 is formed with several radially directed openings 3 that are equally spaced from each other circumferentially of the ring. In the drawings (Fig. 3) there are three of such openings which are elongated circumferentially of the ring, and the space between each adjacent pair is of a length equal to the length of each opening, there-

by providing an imperforate segment 4 of said ring between each such pair of openings.

On the side of face plate 1 opposite ring 2 is an annular chamber 5 (Fig. 4), one of the walls of which is defined by said face plate. The interior of this chamber communicates with the opposite side of the face plate by means of equally spaced, elongated, arcuately extending openings 6 (Fig. 3) that are radially outwardly of ring 2 and that are curved longitudinally to follow a circle concentric with ring 2. These openings 6 are relatively close to ring 2 and are of equal length and three in number with the space between each adjacent pair being equal to the length of each opening. The ends of each opening 6 are respectively in planes that extend radially from the axis of ring 2 and through the ends of each imperforate segment 4 that is between each adjacent pair of openings 3 in ring 2. Thus an opening 6 is just outwardly of each such imperforate segment, while the face plate 1 is imperforate outwardly of each opening 3.

The rotor of the compressor may comprise a plurality of blades 8 that are here represented by the webs between adjacent pairs of radially extending open-ended passageways 9 formed in a circular disk 10 that is centrally secured on a shaft 11. Shaft 11 may extend at one or both ends through packing boxes 12 in one or in two opposite sides of a closed housing 13, and rods 14 or any other suitable means may be secured to the marginal portion of face plate 1 for supporting the face plate rigid within said housing and in the desired position relative to the rotor. The passageways 9 may be cylindrical or rectangular and are equally spaced from each other in an annular row concentric with the central axis of the disk 10 and ring 2.

The disk 10 is formed with an annular, laterally opening recess 15 that extends across the passageways 9. The ring 2 is adapted to slidably fit in said recess when the ring and recess are coaxial, and the openings 3 are arranged so as to register with a plurality of said passageways when the ring is in said recess and the face plate is in sliding engagement with one flat side of disk 10 (Fig. 4). In the drawings (Fig. 2), it will be seen that three of the passageways 9 may at one time be in full registration with each of the openings 3 while the imperforate segments 4 extend across the three openings between each set of three that are in such registration.

For convenience and for clarity the numerals 55 8 will be used to refer to the so-called blades

or webs between the portions of passageways 9 that are outwardly of ring 2, and these blades will be termed the "outer impeller." The blades are webs that are between the adjacent passageways inwardly of ring 3 are designated 18 and these will be called the "inner impeller."

Extending over the outer open ends of the passageways 9 outwardly of the outer impeller are deflecting vanes 19 (Fig. 3) that function according to Bernouilli's energy principle for converting the velocity of a fluid discharged from said passageways into pressure head by gradually slowing up the said velocity.

The passageways 9 are each provided with an opening 20 closely adjacent ring 2. These openings are in an annular row concentric with the ring and they are adapted to register with openings 6 in face plate 1 and to be scanned by the imperforate portions between said openings 6 upon rotation of shaft 11 and disk 10.

The disk 10 is formed with an annular row of passageways 21 extending transversely therethrough, each of which communicates at one end with the passageway 9 of the inner impeller inwardly of ring 2, while the opposite end of each such passageway 21 opens outwardly of disk 10. Each such passageway 21 is relatively small in diameter as compared with openings 20 or with passageways 9.

The disk 10 may also be formed with an annular row of radially extending outwardly opening ducts 22 that open at their inner ends into recess 15. These ducts may be alongside each passageway 9 and each web 8 of the outer impeller.

The compressor may be mounted vertically within the housing 13 as seen in Fig. 1, or in any other desired position, such as horizontal. In whatever position the compressor is mounted the liquid 23, which may be water, oil, or other free flowing liquid, covers same, and a gas pipe or conduit 24 extends from chamber 5 out of the liquid and housing to the atmosphere or to any desired source of gas. A check valve 25 is provided in said conduit.

The inner ends of passageways 9 in the inner impeller are in communication with the liquid 23 through an opening 26 in face plate 1 and preferably a plurality of equally spaced blades 27 may extend inwardly in continuation of the inner ends of some of the blades or webs 18, these blades 27 being part of the inner impeller and extending past the edges of the opening 26 toward the shaft 11. They function to prevent swishing of the liquid and direct the same into the passageways 9 when the disk 10 is rotated.

In Fig. 2 the liquid is indicated by dash lines and the gas is indicated by stippling. The solid heavy black arcuate lines indicate the segments 4 while the open spaces in continuation of and connecting said black lines indicate the openings 3.

In the compressor illustrated and described, there are three complete cycles from intake of gas to compression performed simultaneously. The number of passageways 9, and the number of openings 6 greatly determine the number of such cycles.

In describing the operation, Fig. 3 will be employed and only one cycle will be described, it being understood that the shaft 9 of the rotor is revolved by any desired means, such as a motor 28 (Fig. 1).

Referring back to Fig. 2, it will be assumed that the rotor, which is disk 10, is rotated clockwise. The ring 2 having openings 3 and segments 4 is

held stationary. The water or liquid 23 that is in the housing 13 is drawn into the compressor through central opening 26 in face plate 1 and then is moved outwardly under centrifugal force through passageways 9.

At position 30 (Fig. 2) where one of the segments 4 has just closed one of the passageways 9 to flow of liquid therethrough from the inner impeller to the outer, it will be noted that said passageway is filled with the liquid. However, due to centrifugal force, the liquid in the outer impeller will be moved outwardly in the outer impeller to produce a negative pressure or suction adjacent ring 2. As the opening 6 is in communication with the passageway 9 of the outer impeller at position 30 and at the next succeeding positions 31, 32 the gas or atmospheric air, indicated by stippling, will be drawn into the outer impeller to fill the void thus produced. In

the meantime the liquid in the inner impeller at positions 31, 32, or in passageway 9 of the inner impeller will be restrained by segment 4 from following the liquid and gas in the outer impeller, but just as soon as the passageway 9 advances beyond segment 4 this liquid in the inner impeller is permitted to rush out following

the air that is entrapped in the outer passageway 9 of the outer impeller, as indicated in positions 33, 34, 35, the said air being compressed and ejected into the liquid 23 in housing 13 for rising into the compressed air space 36 at the top of the housing (Fig. 1). At positions 33, 34, 35 the outer impeller is, of course, out of communication with the gas source or with the atmosphere since the opening 6 terminates just beyond position 32. Following position 35, the same cycle is repeated, and, as already explained, three such cycles are simultaneously carried out with each 120° movement of the rotor, or nine complete cycles are produced with each full revolution of the rotor that is herein illustrated. With a larger rotor a greater number of such cycles is possible.

In the foregoing description of the operation it will be apparent that the gas supply is at a higher pressure than the space or void that is produced by the liquid being thrown out of the outer impeller by the centrifugal force, and normally such higher pressure is normal pressure or atmospheric pressure so that the gas will flow into said space and there is a negative or less than atmospheric pressure in said space.

The liquid in the inner impeller is at a greater pressure than the pressure of the liquid 23 in the housing due to centrifugal force imparted thereto by rotation of the rotor. Inasmuch as the gas drawn into the outer impeller is at a lower pressure than the pressure on the liquid in the housing and in the inner impeller, as soon as the liquid in the inner impeller is released the gas is compressed by equalization of pressures.

The centrifugal force that is imparted to the liquid in the rotor is determined by the R. P. M. thereof, the size of the rotor and the density and viscosity of the liquid. The guide vanes 19 are, of course, important for converting the velocity of the liquid discharged into pressure energy.

In order to prevent any possible objectionable leakage of water or liquid past ring 2 and into the outer impeller during the time when the segments 4 interrupt the flow of liquid through passageways 9, we provide the passageways 22, which passageways open at their inner ends into recess 15 at points between the outer edge of ring 2 and the passageways 9. Thus any liquid

that may leak past the ring from the inner impeller will flow out of the passageways 22 before reaching the passageways 9 that are in the outer impeller.

Inasmuch as compression takes place between the liquid bodies in the outer impeller, one of which bodies is in communication with the liquid 23 in housing 13, it will be seen that heat transmitted to said liquid is immediately dissipated in the large body of liquid in said housing, since the liquid in the outer impeller of the compressor is discharged into said housing and may not be recirculated through the compressor for a considerable time. Thus isothermal compression is effected.

Inasmuch as the degree of compression of the gas supply in housing 13 is dependent upon the capacity of the rotor to draw gas into the outer impeller, and which latter capacity is dependent upon the centrifugal force being adequate to overcome the pressure of the liquid in housing 13, it will be seen that the work stroke of the compressor is the suction stroke and not the compression stroke.

As to lubrication, which is a serious problem in the usual sliding-vane-type compressors, no such problem is here presented, since water itself if used as the liquid 23 is a sufficient lubricant, or oil may be used as the liquid if desired.

The rotor constitutes the only moving part of the compressor and this may be fabricated in one or several pieces and face plate 4, ring 2, and the walls of chamber 5 may be made in one or several pieces if desired. In the drawings the several parts of the compressor, such as those above mentioned, are shown as being integral where they are respectively either parts of the face plate or of the housing, but this is merely for clarity and is not a structural limitation. However in any event, the concentricity of parts renders the manufacture thereof quite simple, and at no time is the rotor unbalanced, therefore the action is smooth.

If desired and to eliminate noise due to the water hammer action when the segments 4 interrupt the flow of liquid in passageways 9, I provide openings 21 as described, that will relieve such hammer, which ports relieve the sudden shock by venting into the main body of liquid in the housing.

Description of Figs. 5 and 6

The main difference between the compressor illustrated in these figures and the preceding ones is that in the present instance there is no centrifugal force exerted on the liquid forcing it into the outer impeller. The movement of liquid into the outer impeller is due to the difference in pressure between the liquid in the housing 13 and the gas that is admitted into the outer impeller before compression thereof.

A common feature between the compressor of Figs. 1 to 4 and the compressor of Figs. 5, 6 is the ring 2, which will bear the same number in Figs. 5, 6. Other features are similar although not identical.

In Figs. 5, 6 a pair of stationary face plates 40, 41 are provided in spaced opposed relation, and a chamber 42 at the outer side of plate 40 and centrally thereof is provided for admission of gas to between the two plates, the plate 40 being centrally apertured for passage of such gas. A gas inlet conduit 43, similar to conduit 24 of Fig. 1, is provided for admission of gas into said chamber.

Rotatably fitted in a central aperture in face

plate 41 is disk 44 of the rotor, which disk is centrally secured on shaft 45 for rotation, the latter being connected with any suitable source of power for causing such rotation.

5 The face plate 40 carries the ring 2 which is identical in every respect with the ring 2 of Figs. 1 to 4, having openings 3 therein with imperforate segments 4 therebetween (Fig. 5).

The inner and outer impeller of Figs. 5, 6 respectively comprise an inner annular row of equally spaced radially extending blades 46 (Fig. 5) secured to the rotor disk 44, and an outer annular row of equally spaced radially extending blades 47 also secured to disk 44. The ring 2 is disposed between the adjacent edges of the blades 46 and blades 47.

10 The number of blades 47 may vary, although in Fig. 5 they correspond to the number of blades or ribs 8 of Figs. 3, 4 and as the edges of their blades opposite plate 41 are in substantially sliding contact with the face plate 40, they coact with the latter face plate and with plate 41 and with each other to provide radially extending passageways 48 that are open at their outer ends, while their inner ends are at ring 2. Thus upon rotation of disk 44 the inner ends of the passageways will be intermittently opened and closed by segments 4 and openings 3 in exactly the same manner as passageways 9 of the outer impeller in Figs. 3, 4 are opened and closed.

20 Both plates 40, 41 are provided with openings 49 therein that are in opposed relation and that correspond with openings 8 in Figs. 3, 4 in number and position.

25 Inasmuch as the compressor of Figs. 5, 6 is to be mounted in a liquid in a closed housing in the same manner as the compressor of Fig. 1, it will be seen that as the rotor disk 44 is rotated, the liquid will be drawn through openings 49 into passageways 48 for ejecting radially outwardly from the latter. Such admission to said passageways is only during those times when blades 47 are scanning the openings 49, and at such times the inner ends of passageways are closed.

30 Extending over the outer ends of passageways 48 are deflector vanes 50 that function the same as the vanes 19 of Figs. 1 to 4.

35 In operation, upon rotation of disk 44 by any suitable means, the liquid in which the compressor is immersed will be thrown outwardly by centrifugal force due to revolution of the blades 47 of the outer impeller, thus creating a low pressure zone adjacent ring 2 that will be filled by gas from the inner impeller at the points where the openings 3 occur. The liquid for compression of said gas will flow into said outer impeller laterally through openings 49 as soon as the blades come to said openings, and at which time the imperforate segments 4 close the inner ends of the passageways 48.

Description of Figs. 7 and 8

The invention as disclosed in these illustrations differs mainly from the other forms of the invention in that the liquid may be thrown out of the outer impeller laterally instead of by centrifugal force, and also the gas may move laterally in the rotor instead of radially. This form of the invention is particularly suitable for producing a relatively large volume per minute of relatively low pressure gas, but gas at a pressure above normal.

40 The same interrupter ring 2 with openings 3 and imperforate segments 4 may be used as in the preceding forms.

The ring 2 is rigid with a face plate 60, said plate being formed with openings 61 therein that correspond with openings 6 or 49, and an annular chamber 62 having a gas line 63 in communication therewith is provided for supplying gas to be compressed to said openings.

The rotor comprises a disk 64 that carries an annular row of angularly set blades 65 outwardly of ring 2 and positioned to scan openings 61, said blades being of the blower type and adapted to move fluid axially of the row thereof the same as the blades of a fan. The blades 65 also scan the openings 3 in ring 2, and inwardly of the ring 2 are radially extending blades 66 secured to disk 64 for movement with the latter.

A central opening 68 in face plate 60 admits liquid to the inner impeller blades 66 for movement radially outwardly through openings 3 in ring 2 to the outer impeller.

As in the preceding views, the imperforate segments 4 between openings 3 in the ring 2 are positioned to extend the length of the openings in the face plate. Thus upon revolution of the rotor 64 the liquid admitted to the inner impeller will be thrown outwardly by centrifugal force and upon interrupting this outward movement a space of negative pressure will occur outwardly of ring 2 that is immediately filled with gas or air, and as the liquid is thrown laterally outwardly of the outer impeller the gas supply will be cut off and the liquid confined in the inner impeller by the imperforate segments 4 will be released to follow the air, upon which an equalization of pressure in the gas relative to the liquid will occur and the compressed air will be released in housing 13, or the like, for building up the gas pressure therein.

Instead of the deflecting vanes previously used, we provide stationary, radially extending blades 70 for slowing down the velocity of the fluid ejected from the rotor and for removing the whirl velocity component so as to straighten out the flow.

It is obvious, of course, that the gas could be admitted to the inner impeller and the liquid to the outer impeller, although in such an instance it might be desirable to provide inlet guide blades like blades 70 at the side of the face plate as well as at their present positions.

Comparison of all forms of invention illustrated

A comparison between all forms of the invention herein described and illustrated will show a common principle of utilizing two fluids of different densities, one of which is compressed between bodies of the other and then released under pressure for storage or use. In all forms of the invention there is an alternate admission of fluid of different pressures from separate paths into a single path in alternate relationship in the latter path wherein equalization of pressures occur. Also in all forms of the invention dynamic pressure in a liquid as well as the static pressure thereof is transmitted to successive charges of gas in said liquid for gradually building up the pressure in accumulated charges of such gas.

Other similarities than those mentioned herein will be obvious.

The invention as illustrated in Figs. 1 to 4 is particularly suitable for high pressures, and in all forms of the invention it is obvious that a plurality of compressors can be used on a single drive shaft, and also single units having several rotors for compressing gas in several stages can be employed. The invention as herein illustrated and described is intended to be merely illustra-

tive of the invention, and not restrictive thereof.

Having described our invention, we claim:

1. A compressor of the character described comprising a closed housing containing a body of liquid and a space for gas under pressure, an annular row of impeller blades immersed in said body of liquid and supported for revolving about the central axis of said row, means so supporting said row of blades, a plurality of spaced inlets for admitting liquid in said housing to the blades of said row at spaced points for propulsion by said blades upon such revolution of said blades, means obstructing the admission of such liquid to said blades between said spaced points, means for admitting gas to said blades between said spaced points only, and said impeller blades being exposed to discharging liquid admitted thereto into said housing at all points during revolution of said blades about said axis, a plurality of deflector vanes positioned in the path of the liquid adapted to be discharged by said impeller blades for converting the velocity of the discharged liquid into pressure head, one of the ends of each of said vanes being closely adjacent said blades and said vanes extending from said ends progressively increased distances outwardly of said blades in the direction of travel of the latter.

2. A compressor of the character described comprising a closed housing containing a liquid and a space for gas under pressure, an inner annular row of impeller blades immersed in said liquid and supported for revolving about the central axis of said row, said blades being arranged radially about said axis with their inner ends communicating with said liquid for moving said liquid radially outwardly for discharge centrifugally from the outer ends of said blades, a stationary interrupter ring extending over the outer ends of said blades formed with a plurality of spaced openings for said discharge of such liquid therethrough, an outer annular row of radially arranged impeller blades concentric with said inner row and around the outer side of said ring, means supporting the blades of said inner row and outer row for simultaneous rotation in the same direction about their common axis, means for admitting gas into the annular path of movement of the outer row of blades at points where said interrupter ring closes the inner row of blades to said discharge, said blades of said outer row being open to discharge into said housing at their outer ends, and means extending over the outer ends of the blades of said outer row and spaced therefrom for reducing the velocity of liquid discharged from said outer row, said means being deflector vanes, and one of the ends of each of said vanes being closely adjacent the outer ends of said blades and said vanes extending from their said ends progressively increased distances outwardly of said blades in the direction of travel of the latter.

3. A compressor of the character described comprising a rotor, a closed housing containing a body of liquid in which said rotor is immersed, said rotor including blades secured thereto for causing a relatively rapid flow of part of said liquid in said body in one general direction relative to the axis of said rotor, means for rotating said rotor, means for substantially simultaneously interrupting a portion of said part while permitting the remainder to continue its flow and for admitting a gas at normal pressure into said part behind said remainder during said rotation of said rotor, and means for simultaneously releasing the said interrupted portion and causing

the same to follow said remainder and stopping said admission of gas to behind said portion, said means for interrupting said portion and for releasing the portion so interrupted comprising a ring formed with imperforate segments and openings between said segments, said ring being positioned to intercept the path of said liquid, and said rotor including radially outwardly directed discharge openings for said remainder opening directly into said body of liquid, deflecting vanes 10 over said openings spaced progressively outwardly of said rotor from one of their ends respectively.

4. A gas compressor of the character described comprising a closed housing containing a body of liquid and enclosing a space over said body for gas under pressure, a rotor wholly immersed in said body of liquid, said rotor comprising a pair of concentrically arranged annular coplanar rows of radially extending impeller blades providing 20 an inner and an outer row thereof, means supporting said rows of blades for rotation together in the same direction about their common axis, a central inlet for admitting the liquid of said body to the inner row of impeller blades for outward movement of said liquid by centrifugal force upon said rotation of said rotor, equally spaced imperforate stationary segments of a ring positioned between said rows of blades for interrupting said movement of said liquid from said inner row of blades to said outer row of blades, means for admitting gas from outside said housing into the path of travel of said outer blades adjacent said segments and for their full lengths, said outer

5 blades terminating in said body of liquid for ejection of the liquid and gas between them directly into said body, and deflectors respectively extending progressively outwardly of the said outer row of blades and over the outer ends thereof for reducing the velocity of the said liquid ejected from said outer row.

5. A compressor of the character described comprising an annular inner row and an annular outer row of radially disposed impeller blades, said rows of blades being coplanar and concentric, and means supporting said blades for movement together about their common axis, a housing enclosing said blades formed with a central inlet for admitting fluid to the inner ends of the blades of said inner row, a stationary interrupter ring positioned between said rows formed with alternate perforate and imperforate sections for opening and closing communication between the said rows of blades periodically as said blades are revolved, openings formed in said housing for permitting continuous circulation of fluid through the inner impeller blades at all times independently of said ring, and means for admitting fluid different than that adapted to be admitted to said inner row to the inner ends of the impeller of said outer row at said points where the imperforate sections of said ring extend between said rows, and the outer ends of the blades of said 30 outer row being open to discharge of fluid outwardly thereof at all times.

WILLIAM FELZER.
SAM WEINBERG.
